UNITED STATES PATENT OFFICE.

WILLIAM R. DAVIS, OF SPARTANBURG, SOUTH CAROLINA.

RAILWAY-CROSSING SIGNAL.

Application filed August 29, 1927. Serial No. 216,233.

The object of this invention is to provide a simple electrical apparatus whereby a train approaching a highway-crossing will automatically operate a traffic signal, 5 preferably of the visual type, and, when it passes the crossing, will restore the signal to normal; whereby accidents to vehicles at the highway-crossing will be prevented, as more fully hereinafter set forth.

10 In the drawing—

Fig. 1 is a plan view of a double track with my system applied thereto;

Fig. 2 is a plan view of a single track with my system applied thereto;

15 Fig. 3 is a view partly in side elevation and partly in section of a preferred form of electric lamp signal;

Fig. 4 is a vertical sectional view of the release-box;

20 Fig. 5 is a detail perspective view of the release-switch;

Fig. 6 is a vertical sectional view taken through the signal-setting-box;

25 Fig. 7 is a horizontal sectional view taken through the same;

Fig. 8 is a detail perspective view of the flange-operated device in the setting-box.

In the drawing, 10 designates the signal-setting-boxes; 11, the signal-restoring or 30 releasing boxes; and 12, the light signal which may be located at any point where it may be readily seen by persons approaching the track-bed from either direction on the highway-crossing. The setting-box 10 is to be placed any suitable distance from the crossing, and the box 11 is to be placed at any suitable distance beyond the crossing. The two boxes and the signal are connected by two wire conductors 13.

40 The signal-setting appliance consists of a casing 14 which is adapted to be bolted to a railway-tie alongside the rail. Projecting through a slot in the side wall of the casing which is closest to the rail is an arm 15 which curves upwardly so as to lie in the path of the flanges of the wheels on the railway vehicle, so that, as a wheel passes this arm, the arm will be swung forwardly far enough to permit the wheel-flange to pass.

45 50 This arm 15 is provided with a curved guide 16 which works in companion arcuate slots formed in a box 17 set in the casing 14, the upper slot being formed in the cover 18 of this box and the other being formed in the bottom of the box.

To hold the arm 15 in normal position,

i. e., at right angles to the rail, I employ a flat spring 18 whose inner end enters a socket 19 formed in the adjacent face of the guide 16 and whose outer end is rigidly anchored 60 to the outer wall of the box 17. To add flexibility to the spring arrangement and at the same time make the spring action strong enough to prevent the arm 15 being swung back-and-forth manually, by mischievous 65 persons, I employ a pair of coil-springs 20, one being on either side of the flat spring 18. The inner ends of these coil-springs bear on opposite sides of the flat spring 18 with equal pressure, and their outer ends 70 engage the side walls of the box 17, suitable projections 21 being employed on the spring 18 and box 17 to hold these coil-springs in position. It will be observed that with this spring arrangement, the arm 15 strongly 75 tends to return to normal, operative position after it is swung in either direction.

An arm 22 is attached to the guide 16 and extends through the opposite slot in the bottom thereof and outwardly to a point 80 back of the box 17. When the arm 15 is swung forwardly by the wheel-flange, the outer end of this arm 22 closes an electric switch 23 and thus lights the warning signal which, as stated, is in circuit through the 85 medium of conductors 13, with this switch, it being of course understood that either a local battery or current from a nearby main may be used to light the signal.

To maintain the circuit in closed condition 90 after the switch 23 is closed, I employ a latch 24 which is pulled down by a magnet 25 when the circuit is closed, thus putting the hook-end 26 of the latch into engagement behind a shoulder 27 formed on the adjacent 95 end of the guide 16, thereby locking the arm 15 in abnormal position and holding the circuit closed until the magnet 25 is deenergized by breaking the circuit at the release-box further on on the track-bed. The latch 100 24 is provided with a spring 28 which normally tends to lift the latch out of engagement with the shoulder 27, so that, when the magnet is deenergized, the latch will fly up and the flange-arm 15 will swing back to 105 normal position.

The release-box is constructed substantially the same as the setting-box except that the latching magnet 25 is unnecessary and, instead of a circuit-closer, I must employ a 110 circuit-opener, as shown at 29. As a warning signal, I have shown an electric lamp

mounted in a casing in whose walls is mounted a pair of red lenses 30, but it will be understood that I may employ any other type of signal.

5. To insure operation of the flange-arms 15, I prefer associating with each one of the boxes, at the opposite sides of the track-bed, a guard-rail 31.

It will be understood that the two conductors 13 may be housed in galvanized conduits or lead cables and that these conduits or cables will be connected to the cast-iron switch-boxes and light-casing; the conduits or cables being arranged along the rails, as 15 shown, and held in position with metal clamps fastened to the cross-ties.

What I claim as new is:

1. In a railway crossing appliance, a casing adapted to be fastened to the roadbed alongside the rail, an arm working through 20 a slot in said casing adjacent to the rail adapted to be actuated by a passing wheel.

flange, a curved guide carried by said arm, arcuate guide-ways for said curved guide, a spring appliance for normally holding said arm in operative position, a switch-closing device carried by said guide, and an electromagnetic latching device adapted to engage and hold said guide in abnormal position when said switch is closed.

2. In a railway-crossing signal system, a casing adapted to be fastened to the roadbed alongside a rail, a flange-operated arm projecting through a slot in said casing lying in the path of the wheel-flange, a curved guide 35 attached to said arm and means within the casing for guiding said guide in an arcuate path, spring devices for holding said guide and said arm in normal operative position, and a switch-actuating element attached to 40 said guide so as to be moved therewith.

In testimony whereof I hereunto affix my signature.

WILLIAM R. DAVIS.
